UNITED STATES PATENT OFFICE

MAX REISS, OF NEW YORK, N. Y.

BOOK COVER

Application filed June 22, 1932. Serial No. 618,628.

This invention relates to new and useful improvements in book covers, and more particularly it pertains to protective covers for books.

- 5 A feature of the invention resides in a novel construction whereby a book cover constructed in accordance with the present invention may be used with books of various sizes within certain limitations.
- 10 A further feature of the invention resides in a novel construction whereby the protective cover may be readily attached to or removed from a book with ease and facility.

15 A still further feature of the invention resides in a construction which is cheap and economical of manufacture and highly efficient for the purposes for which it is intended.

20 The invention will be clearly understood from the accompanying drawing which illustrates the invention in its preferred form and the following detailed description of the construction therein shown.

In the drawing;

25 Figure 1 is a perspective view of a book with a cover constructed in accordance with the present invention partially attached thereto, and illustrating the manner in which the protective cover is retained in position upon the book,

30 Figure 2 is a view in end elevation of a book having a protective cover constructed in accordance with the present invention, attached thereto, and;

35 Figure 3 is a transverse sectional view, taken on the line 3—3 of Figure 1.

A book cover constructed in accordance with the present invention consists of a rectangular sheet of suitable flexible material which constitutes the main body portion 5 of the cover.

40 The sheet ordinarily would be of greater length than width although other shapes of blanks may at times be resorted to in the manufacture of covers for use on books of other than standard shapes and sizes.

For the purpose of illustration, I have chosen a sheet of rectangular form and of greater length than width, the end edges of the sheet being designated 6 and its side edges being designated 7, its inner face being des- 50 ignated 8 and its outer face 9.

In applying the cover to a book, the side edges thereof are folded inwardly upon the inner face thereof as at 10 to provide open book cover receiving pockets 11 at each end 55 of the cover. It is to be understood that the lines of fold 10 are not fixed, but are determined solely by the size of the book cover to which the protective cover is to be attached, thus rendering each protective cover capable 60 of use on books of many different sizes.

When the sheet has been folded inwardly to provide the pockets 11, a book cover such as 15 is inserted into the pocket at one end as illustrated in Figure 1 of the drawing, 65 after which the protective cover is wrapped around the book and the other cover 16' of the book inserted into the cover receiving pocket at the other end of the blank. The protective cover may now be adjusted with relation to the book so that it will lie smoothly thereon as illustrated in Figure 2 of the drawing.

Means is provided to retain the protective cover against accidental displacement or undue shifting relative to the book cover and as herein illustrated, this means consists of longitudinally extensible strips 15, each of which has a hook 16 for engagement with the end edges of the book covers. 70 75 80

These extensible strips 15, I prefer to construct from elastic webbing and they are secured to the inner face 8 of the blank at each corner thereof as at 18, with the longitudinal axis of each strip extending substantially at 85 right angles to its respective side edge 7 of the blank, or at such other angle that the strips 15 extend substantially transversely of the protective cover. The hooks 16 herefores mentioned are preferably formed 90

from relatively thin stiff material such as light metal, celluloid or the like and are secured to the free ends of the strips in any desired manner.

- 5 When the protective cover has been applied to a book as above described, the strips 15 and their hooks 16 will be positioned between the book covers and the adjacent portions of the protective cover with the hooks 16 un-
10 attached to the book covers, although in placing the protective cover on the book, two of the hooks may be engaged with the book covers before the protective cover is completely positioned thereon as illustrated in
15 Figure 1. With the parts in the position described, it is only necessary to partially open the book in which position all of the strips and hooks will become accessible and may be engaged with the book covers to secure the
20 protective cover in position.

It will be noted that in attaching the hooks to the book covers, each hook is engaged with that edge of the book cover opposed to the edge adjacent the attachment of the strip by
25 which the hook is carried. This operation places the strips 15 under sufficient tension to insure against accidental displacement of the hooks relative to the book covers thereby holding the protective cover in place upon
30 the book and also stretching it smoothly thereover.

When the protective cover has been finally positioned upon a book, the strips 15 and the major portions of the hooks 16 will lie be-
35 tween the book covers and the adjacent portions of the protective cover and will be hid-
den from view except for a small portion of each hook as illustrated in Figure 2.

From the foregoing, it will be apparent
40 that the present invention provides a new and novel protective cover for books which is capable of use with books of different sizes, which is easily and quickly removable or attachable to books and which, when in position upon a book, will be held securely in proper position thereon.

While the invention has been herein disclosed in a preferred form, it is to be understood that it is not to be construed as limited
50 to the specific construction herein shown, and that it may be embodied in such other forms as rightfully fall within the scope of the appended claims.

Having thus described the invention, what
55 is claimed as new, and what it is desired to secure by Letters Patent of the United States, is;

1. A protective cover for books comprising
60 a rectangular sheet of suitable material
adapted to be folded to receive the covers of a book, and means carried by each side of said sheet for engagement with a book cover for holding the protective cover in position upon a book.
65 2. A protective cover for books comprising

a rectangular sheet of suitable material adapted to be folded to receive the covers of a book, and means carried by each side of said sheet for engagement with a book cover for holding the protective cover in position upon a book, said last mentioned means being extensible whereby to adapt the protective cover to books of various sizes. 70

3. A protective cover for books comprising a rectangular sheet of suitable material adapted to be folded to receive the covers of a book, and means carried by each side of said sheet for engagement with a book cover for holding the protective cover in position upon a book, said last mentioned means comprising longitudinally extensible members, and a hook for engagement with an edge of a book cover, there being a hook carried by each of said longitudinally extensible members. 75

4. A protective cover for books, comprising a rectangular sheet of flexible material, and means at each corner of said sheet for attachment of the cover to a book, said means comprising an elastic strip secured at one end to the inner face of the protective cover and having a free end, and a book cover engaging hook carried by the free end of each of said elastic strips. 80

5. In combination with a book, a removable protective cover therefor, said protective cover comprising a rectangular sheet of flexible material having its side edges folded inwardly of its body portion to provide open book cover receiving pockets, an elastic strip secured to each end of each inwardly folded side edge and extending transversely of the sheet, and a book cover engaging hook secured to the free end of each of said elastic strips. 85

Signed at New York city, Bronx County, 105
this 20th day of June 1932.

MAX REISS.
